MACHINE FOR GENERATING MULTISIDED APERTURES

Hans Joachim Schröder, Dessau, Germany, assignor to Junkers Flugzeug-und Motorenwerke Aktiengesellschaft, Dessau, Germany, a corporation of Germany

Application September 3, 1938, Serial No. 228,307
In Germany September 6, 1937

6 Claims. (Cl. 77—61)

This invention relates to a machine for generating multi-sided apertures which are sufficiently accurate in form to fulfill all ordinary requirements.

My invention is based on the fact that certain cycloids are generated around the perimeters of polygons having rounded corners; hypocycloids are important in the development of apertures which are multi-sided in section. The curves referred to are utilized in the following manner: While the cutting edge of my tool rotates once about the axis of the toolholder, the latter also rotates several times in the opposite direction about the axis of the multi-sided aperture being generated. Moreover the ratio of the speeds of rotation of the tool about these two axes determines the number of sides of the multi-sided aperture. Again to produce multi-sided apertures having flat sides the radial distance of the cutting edge of the tool from its axis must be correctly proportioned to the distance between the tool axis and the axis of multi-sided aperture.

It is an object of the invention to provide a machine for generating multi-speed apertures all the lateral walls of which are of equal length and disposed at a common angle to one another, and by which all multi-sided apertures cut when the device has once been set are identical. Moreover the machine may be so set that all the sides of the multi-sided aperture are flat.

Another object of the invention is to provide a machine for generating multi-sided apertures which is simple in construction, has only few moving parts, requires very little attention when in operation, and which does not subject the cutting tool to excessive wear.

A further object of the invention is to provide a machine for generating multi-sided apertures wherein the tool spindle is rotated through gearing, and wherein the spindle, which rotates at a constant speed, is simultaneously rotated about a second axis in alignment with longitudinal axis of the aperture being generated.

Yet another object of the invention is to provide a machine for cutting multi-sided apertures wherein the ratio of the cooperating gears controls the number of sides generated around the aperture; and wherein by varying the radial length of projection of the cutting tool from the tool spindle axis the length of the sides of the multi-sided aperture generated is changed.

Some of the preferred embodiments of the invention are hereinafter more fully described with the aid of the accompanying drawings in which:

Figure 1 is a longitudinal section showing one embodiment of the invention.

Figure 2 is a section on the line II—II of Figure 1.

Figure 3 shows a longitudinal section of a somewhat modified construction.

Figure 4 is a section on the line IV—IV of Figure 3.

Figure 5 is a longitudinal section showing another modification.

Figure 6 is a section on VI—VI of Figure 5.

Figure 7 is a partial longitudinal section showing a slight further modification.

Figure 8 is a longitudinal section showing another modified form of the invention wherein the axis of the tool spindle is inclined to the axis of the multi-sided aperture to be generated.

Figures 9 and 10 are enlarged sectional details showing methods of adjustably mounting the tool for angular movement upon the tool spindle.

Referring first to Figures 1 and 2, the drive spindle or shaft 1 has a shank 2 mounted therein for rotation therewith. The shank 2 projects beneath the spindle 1 and is rotatably supported in a fixed frame 3. The said shank 2 is also provided with an eccentric tapered bore to receive a cone 4. Fixed eccentrically upon the latter is a gear 5, and projecting from the opposite face of the said gear and concentric therewith is a guide pin 6 which is rotatably mounted in a bearing 7 formed in a movable guide 8. Mounted for rotation in the latter is a tool spindle 10 upon the upper extremity of which a gear 9 is concentrically fixed which meshes with the gear 5. 11 denotes the operating extremity of the tool spindle 10 which in the present instance is integral with the latter. 12 is a tool bit carried by the spindle 10 and projecting radially therefrom to cut the lateral faces of an aperture 13 in the work. 14 denotes a carriage having aligned slides 15 and 16 formed thereon which are longitudinally movable in aligned ways 17 and 18 provided in the frame 3. The carriage 14 also has another slide 20 integral with it which is movable along ways 19 formed in the guide 8. The slide 20 is disposed at right angles to the slides 15 and 16.

Briefly, the operation of the device is as follows: As the drive spindle 1 rotates it turns the tool spindle 10 through the gearing 5 and 9, and due to the fact that the axis C of the gear 5 and its pin 6 is spaced a distance r from the axis B of the drive spindle 1 rotation of the latter moves the guide 8 around an axis M which must coincide with the axis of the multi-sided aperture to be generated. Moreover the axis M is parallel

to and spaced from the axis A of the tool spindle a distance r^1 which is equal to the distance r between the axes B and C.

The circular path of movement of the guide is insured by the carriage 14, movement of which occurs simultaneously in two directions at right angles to one another along the ways 17 and 18 and 19 caused by the rotation of the eccentric pin 6. The distance r is regulated by the rotary position of the cone 4 in the eccentric bore of the shank 2 because the said cone is eccentric with the gear 5 and therefore may be turned so that its eccentric mounting in the shank 2 either complements or offsets the eccentricity of the gears 5. The ratio of the teeth in the two gears 5 and 9 controls the shape of the multi-sided apertures generated; with these gears proportioned 1:2 a triangular aperture is obtained; and when proportioned 1:3 the aperture is made rectangular.

In the modification shown in Figures 3 and 4, 29 denotes portions of a fixed frame in which the extremities of two spaced parallel columns 28 are supported. Bushings 24 eccentrically bored at 27 are mounted for rotation about columns 28 and have gears 25 fixed thereon. A guide 21 has a spindle 22 rotatably mounted therein, and fixed upon the latter is a gear 26 opposite sides of which mesh with the gears 25. Integral with the guide 21 are opposed lateral extensions 23 through which the bushings 24 extend and wherein they are rotatably mounted. A universal joint 30 is secured both to the upper extremity of the tool spindle 22 and also to a drive spindle or shaft 31 which turns about a fixed axis B¹. The eccentricity of the tool spindle 22 relative to the drive shaft 31, which is represented by the distance r^2 between the drive shaft axis B¹ and the axis A¹ of the tool spindle 22, must be equal to the distance r^3 between the axes D of the columns 28 and the axes E of the bushings 24. It is therefore obvious that the rotation of the tool spindle 22 about its own axis A¹ imparts rotation to the bushings 24 through the gearing 26 and 25, and, due to the eccentric mounting of the said bushings upon the fixed columns 28, rotation is also imparted to the guide 21, through which the tool spindle 22 extends, about the said axis B¹. Obviously, in this form of construction the guide 21, the bushings 24 and the gears 25 and 26 may all be moved axially together upon the columns 28 to provide axial feed for the tool spindle 22; moreover in this form of construction the axis B¹ is in alignment with the axis about which the guide 21 is rotated and must therefore be in alignment with the axis of the multi-sided aperture being generated.

In Figures 5 and 6 the tool spindle 32 is eccentrically mounted in a guide 33, and in order to make the view shown in Figure 5 clearer this eccentricity is perpendicular to the plane on which the section is taken. The guide 33 is concentrically supported in a stationary frame 34 so that its axis is coaxial with the axis M¹ of the latter. The guide 33 is in the present instance rotated by means of a belt 35 passing through a suitable opening 36 in the frame 34 and around the guide periphery though other means may be employed for turning said guide. Fixed upon the spindle 32 is a gear 37 which meshes with a gear 38 upon a stub shaft 39 supported in a laterally projecting member 40 integral with the said guide 33. Fixed upon the shaft 39 is a second gear 41 which engages a gear 42 concentri-

cally fixed upon a stationary shaft 42a mounted in the frame 34 concentrically with the axis M¹.

Through rotation of the guide 33 about the axis M¹ the gear 41 rolls around the fixed gear 42, thereby imparting rotation to the spindle 32 about its axis A² and also around the axis M¹ through the gears 38 and 37. The axis M¹ should coincide with the axis of the multi-sided aperture to be generated. In this case the cross sectional form of the aperture is dependent upon the total ratio of the two coaxial pairs of gears. For instance, a 3:2 ratio produces a triangular hole, and a 4:3 ratio produces a rectangular hole.

Figure 7 shows a slight modification of the construction just described and illustrates one means for varying the distance r^4 between the axis M¹ and A², and thus the diameter of the circular path around which the axis of the tool spindle travels as it rotates about its own axis. The bore of the guide 33a is longitudinally inclined and a bushing 54, the periphery of which is correspondingly inclined, is longitudinally movable therein, so that the bore of the bushing is parallel with the axis M¹ and eccentric with the periphery of the guide 33a. Obviously, by adjusting the longitudinal position of the bushing in its guide in the direction of the arrows X or Y the distance r^4 may be varied.

However in order to make this arrangement operative in the construction shown in Figures 5 and 6 the gears 37 and 38 must be changed and another set of larger or smaller diameter used for each vertical setting of the bushing 54, which must therefore be at certain predetermined vertical positions so that the set of gears 37 and 38 employed mesh properly with one another. Similarly such an adjustment may also be employed in the arrangement shown in Figures 3 and 4 by changing the gears 25 and 26 for others of larger or smaller diameter.

Figure 8 shows an inclined tool spindle 43 having a bevel gear 44 fixed upon its upper extremity which travels around an internal gear 46 provided within a stationary housing 45. The axis A³ of the spindle is inclined at an angle α to the axis M² of the frame and intersects the latter at the point K below the said frame. The tool spindle 43 is in its inclined position eccentrically mounted in a guide 47 which is coaxial with the internal gear 46 insomuch that the axis A³ intersects the bushing axis M² at K beneath the bottom of the said guide. The guide 47 is connected to a drive spindle or shaft 48 which is mounted for rotation in the upper portion of the housing 45 and extends therethrough in alignment with the axis M².

When the shaft 48 and the guide 47 are turned the bevel gear 44 travels around the internal gear 46 and the tool spindle 43 is rotated about both axes A³ and M². The proportionate sizes of the gears 44 and 46 control the cross-sectional form of the multi-sided apertures generated by the cutting edge S of the tool 49. For instance, if the ratio of the gears is 3:2 a triangular hole is formed and if the ratio is 4:3 the hole generated is rectangular. From the foregoing, it will be clearly seen that the tool spindle 43 turns both about its axis A³ and about the axis M² of the guide 47. Moreover on account of the inclination of these two axes to one another, the transverse distance between them varies according to the vertical distance of the cutting edge S of the tool above or below their point of intersection K.

The cutting edge S of the tool must be suf-

ficiently spaced radially from its axis A^3 to produce a multi-sided aperture, and the flatness of the sides of the aperture is controlled by the proportionate distance of the cutting edge S from the two axes A^3 and M^2 . Obviously, if the tool is in the same horizontal plane as the point K no eccentric movement of the tool-edge S is obtained.

Figure 9 is an enlarged diagrammatic view showing a modification of the structure shown in Figure 8 wherein the tool spindle 43a is tubular and the point K is located beneath the cutting edge S of the tool 49. Axially movable in the spindle 43a is a rod 52 having a laterally disposed pin 60 projecting therefrom. Formed in the tool spindle 43a is an inclined guide 61 in which a toolholder 50 is slidably mounted. The outer extremity of the pin 60 is a sliding fit in an aperture 50a in the toolholder 50 so that it may slide therethrough as the rod 52 is moved in the tool spindle 43a and the said toolholder is correspondingly moved in the guide 61. In this construction it is obvious that upon feeding the rod 52 in the guide 43a the cutting edge S of the tool 49 must travel along a line $S-K$ parallel with the base of the guide 61 that is at an angle β to the axis A^3 of the tool spindle; and α denotes the angle between the axes A^3 and M^2 .

The arrangement shown in Figure 10 is practically identical to that shown in Figure 9 except that the point K , which again designates the intersection of the axes A^3 and M^2 , is located above instead of beneath the tool 49, and therefore the line $S-K$ lies above instead of beneath the said tool. The rod 53 and the tool holder 51 and the pin 60a correspond to the rod 52, the toolholder 50 and the pin 60 above described. α again denotes the angle between the axes A^3 and M^2 , and β the angle between the line $S-K$ and the axis A^3 .

The purpose of the embodiments shown in Figures 9 and 10 is to provide means, by feeding the rod 52 or 53 in the spindle 43a, for forming multi-sided apertures the walls of which are all uniformly inclined to the longitudinal axis M^2 ; and the latter of course also coincides with the axis of the multi-sided aperture being generated. In other words the apertures thus formed are of different sizes at the top and bottom, thus having the shape of a truncated pyramid.

It will of course be noted from the drawings that as above stated the tool spindle rotates about its own axis in the opposite direction to that in which it travels around the second axis.

While the preferred embodiments of the invention have been described and shown it is understood that further alterations and modifications may be made thereto provided they fall within the scope of the appended claims.

What I claim is:

1. A machine for generating multi-sided apertures comprising a frame, a drive shaft mounted for rotation therein, a guide fixed on the shaft within the frame, an internal gear in the frame, a spindle mounted for rotation in the guide about its axis, said axis being angularly disposed with reference to the guide axis and adapted to intersect the same, a gear on the spindle meshing

with the internal gear through which said spindle is turned by the rotation of the guide, and a tool carried by the spindle, said tool having a cutting edge spaced axially from the point of intersection and displaced laterally from the axis of the spindle.

2. A machine for generating multi-sided apertures comprising a frame, a drive shaft mounted for rotation therein, a guide fixed on the shaft for rotation in the frame, an internal bevel gear on the frame, a spindle mounted for rotation in the guide at an inclination to the guide axis, said guide and spindle axes being adapted to intersect, a bevel gear fixed on the spindle and meshing with the internal bevel gear whereby the spindle is turned by the rotation of the guide, and a tool carried by the spindle, said tool having a cutting edge spaced axially from the point of intersection and displaced laterally from the axis of said spindle.

3. A device for generating multi-sided apertures comprising a frame, a guide mounted for rotation therein, a spindle mounted in said guide, the rotative axis thereof being in offset relation to the rotative axis of the guide, for rotation therewith and for independent rotation within the guide about its own axis, a tool supported by said spindle, said tool including a cutting edge displaced laterally from the rotative axis of the spindle, means for rotating said guide, and cooperating means on said frame and spindle whereby rotation of the guide causes rotation of the spindle about its rotative axis to thereby impart to the cutting edge of the tool a hypocycloidal movement with reference to a circular line about the rotative axis of the guide.

4. Mechanism of the class described comprising a frame, said frame including a circular portion having a driving surface around its internal periphery, a guide rotatable in the frame, a tool spindle rotatable in the guide with its axis of rotation eccentrically disposed with relation to the rotative axis of the guide, said spindle including a circular portion having a driven surface around its external periphery in operative engagement with the driving surface in said frame, means for producing relative rotation of said frame and guide, and a cutting tool positioned by said spindle.

5. Mechanism of the class described comprising a frame, said frame including a circular portion having a driving surface around its internal periphery, a guide rotatable in the frame, a tool spindle rotatable in the guide with its axis of rotation angularly disposed with relation to the rotative axis of the guide, said spindle including a circular portion having a driven surface around its external periphery in operative engagement with the driving surface in said frame, means for producing relative rotation of said frame and guide, and a cutting tool positioned by said spindle.

6. The mechanism set forth in claim 5 wherein in the cutting edge of the tool is laterally displaced from the spindle axis and axially displaced from the intersection of the guide and spindle axes of rotation.

HANS JOACHIM SCHRÖDER.
